United States Patent Office

Des. 210,199
Patented Feb. 20, 1968

210,199

BUILDING

Joe M. Cox, 316½ E. Main St., P.O. Box 828,
Johnson City, Tenn. 37601

Filed Sept. 21, 1967, Ser. No. 8,682

Term of patent 14 years

(Cl. D13—1)

FIG. 4.

FIG. 3.

FIG. 5.

I claim:

The ornamental design for a building, as shown.
